CLAIM

The ornamental design for a telescoping tool with stick handle, as shown and described herein.

DESCRIPTION

FIG. 1 is a perspective view of a telescoping tool with stick handle;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof; and

FIG. 7 is a bottom plan view thereof.

FIG. 8 is a perspective view of a second embodiment of the telescoping tool with stick handle;

FIG. 9 is a front elevational view thereof;

FIG. 10 is a back elevational view thereof;

FIG. 11 is a right-side elevational view thereof;

FIG. 12 is a left-side elevational view thereof;

FIG. 13 is a top plan thereof; and

FIG. 14 is a bottom plant view thereof.

FIG. 15 is a perspective view of a third embodiment of the telescoping tool with stick handle;

FIG. 16 is a front elevational view thereof;

FIG. 17 is a back elevational view thereof;

FIG. 18 is a right-side elevational view thereof;

FIG. 19 is a left-side elevational view thereof;

FIG. 20 is a top plan thereof; and,

FIG. 21 is a bottom plan view thereof.

The broken lines depict portions of the telescoping tool with stick handle in which the design is embodied that are not considered part of the claimed design.
